US00D968692S

(12) **United States Design Patent** (10) **Patent No.:** **US D968,692 S**
(45) **Date of Patent:** **** Nov. 1, 2022**

(54) **VAPORIZER DEVICE**

(71) Applicant: **JUUL Labs, Inc.**, San Francisco, CA (US)

(72) Inventors: **Brandon Cheung**, San Francisco, CA (US); **Carlos A. Dominguez**, San Pablo, CA (US); **Dylan E. Entelis**, Los Angeles, CA (US); **Matthew J. Malone**, Los Angeles, CA (US); **James Monsees**, San Francisco, CA (US); **Zachary T. Scott**, Oakland, CA (US); **John Travis Wettrath**, San Francisco, CA (US)

(73) Assignee: **JUUL Labs, Inc.**, San Francisco, CA (US)

(**) Term: **15 Years**

(21) Appl. No.: **29/825,824**

(22) Filed: **Feb. 4, 2022**

Related U.S. Application Data

(63) Continuation of application No. 29/713,290, filed on Nov. 14, 2019, now Pat. No. Des. 943,160.

(51) **LOC (13) Cl.** **27-02**

(57)

CLAIM

The ornamental design for a vaporizer device, as shown and described.

DESCRIPTION

FIG. 1 is a top, front, and right side perspective view of a vaporizer device of our design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines illustrate portions of the vaporizer device that form no part of the claimed design.

1 Claim, 3 Drawing Sheets
